AIR COMPRESSOR

Application filed August 23, 1927. Serial No. 214,801.

This invention relates to compressing air and has for its principal object the provision of an improved compressor constructed so as to operate with a minimum generation of heat in the compression cylinder.

In the accompanying drawings, I have illustrated a preferred embodiment of my invention, a study of which will make the principles involved clear. In these drawings 10 Figure 1 is a longitudinally vertical section through a double acting compressor constructed in accordance with the present invention, and Figures 2, 3, 4 and 5 are dia- 15 grammatic sections through the compression cylinder showing the position of the parts during successive stages of the compression cycle.

The compressor illustrated in the drawings is of the double-acting type consisting in 20 effect of two compression cylinders in which the actions during each stroke are complementary. As the actions in each cylinder are identical except for this complementary time relation, I shall in general confine the 25 following description to one only, the corresponding parts in the two cylinders being given the same reference numerals, those in the right-hand cylinder being primed.

In the compressor illustrated, 1 designates 30 the compression cylinder and 2 the compression tank or reservoir. Mounted within the cylinder is a primary piston 3, affixed to a piston rod 4 and reciprocated by means of the prime mover illustrated generally at 5. Af- 35 fixed to, and forming part of the primary piston 3 is a cylindrical extension 6 defining a recess in which is seated a secondary piston 7 to which is affixed a sleeve 8 slidably mounted upon the piston rod 4. Interposed be- 40 tween the base 9 of the recess and the inner face of the secondary piston is a compression coil spring 10 designed normally to hold the two pistons flush as illustrated in Figure 1, and a stop 31 is provided for preventing 45 outward movement of the secondary piston beyond the primary. The piston rod 4 is secured to the primary piston through the base 9 which element also forms the base of the corresponding piston 3' operating in the 50 right hand end of the cylinder, and acts as a

cross head for the two. In order to prevent compression of air within the cylindrical extension 6 due to movement of the secondary piston therein, communication with the atmosphere is effected through a bore 11 in the 55 piston rod 4.

Atmospheric air enters the cylinder through a port 12 controlled by means of a poppet valve 13 positively actuated by a pivoted arm 14 connected to a link 15 reciprocated in proper timed relation by means of the prime mover. The cylinder communicates with the tank 2 by means of ducts 16 and 17 entering through the cylinder head and a duct 18 entering through the side wall of the cylinder. Duct 16 is provided with a poppet valve 19 positively actuated by means of a cam 20 on a rotary shaft 21 while communication between the cylinder and the duct 18 is controlled by means of poppet valve 22, 60 positively actuated like valve 13 by means of a pivoted arm 23 connected to a link 24 similarly reciprocated by the prime mover. The duct 17 is provided with a spring actuated outwardly opening valve 25. The spring is set to permit opening of the valve as soon as the pressure in the cylinder exceeds that in the tank.

Outward movement of the secondary piston, 7, which would normally accompany that of the primary piston 3, is prevented by means of a latch 26 on the sleeve 8 against which abuts a pivoted pawl 27 oscillated at the proper time by a rod 28 operated by means of a cam 29 on the cam shaft 21.

The cylinder is provided at the end remote from the intake valve 13 with a by-pass 30, the ends of which enter the cylinder at points spaced apart by a distance substantially equal to the thickness of the primary piston. The function of this by-pass will be made clear in connection with the description of the general operation.

I shall now describe the operation of the compressor with particular reference to Figures 2, 3, 4 and 5. Starting with the parts as illustrated in Figure 2, the primary piston 3 is moved to the left. At this time the poppet valves 13 and 19 are opened and poppet valves 22 and 25 closed. The pawl 27 is in the posi-

tion illustrated, abutting against latch 26 so that although the annular primary piston 3 moves forward, the secondary piston remains fixed and consequently compresses the spring 10. The effect of the forward movement of the primary piston is to move the air in the cylinder which is initially at tank pressure, through duct 16 and into the tank. At the same time the corresponding valve 19' at the other end of the double cylinder is opened so that air at tank pressure enters behind the moving piston 3' in that end of the cylinder. The primary pistons are therefore substantially balanced considering the pressures on their outer faces. Meanwhile, however, atmospheric air has been drawn in through port 12 by the opening of valve 13 and now fills the annular space behind the primary piston 3 while air at tank pressure is being moved into the tank through duct 18'.

When the primary piston 3 reaches the end of its stroke as illustrated in Figure 3 it uncovers the inner port of by-pass 30 thereby connecting the annular space filled with atmospheric air with the space on the other side of the piston which is filled with air at tank pressure. At this point, the valves 13 and 19 are closed, the position of the parts being illustrated in Figure 3.

With the closing of the valves 13 and 19, the pawl 27 is swung out of engagement with the latch 26, thus freeing the secondary piston and permitting the compressed spring 10 to move the secondary piston outward until flush with the primary piston, the position of the parts after this movement being illustrated in Figure 4. As soon as the primary piston uncovers the inner port of the by-pass 30, the air at tank pressure passes into the annular space behind the primary piston and mingles with the atmospheric air that has just been drawn in thereby raising its pressure. It is, of course, not raised to tank pressure because the valve 19 has been closed, but

is raised to some pressure intermediate atmospheric and tank pressure. At this point, the action of the secondary piston comes into play and speeds up the movement of the air through the by-pass into the cylinder at the same time slightly raising the pressure in the entire system. In order to prevent the pressure from rising above that of the tank the valve 25 is provided, automatically opening to relieve any excess pressure in the cylinder.

On the return stroke, primary piston 3 and secondary piston 7 move together. Valve 22 is opened so that air in the cylinder is unquestionably at tank pressure and the air which has just been drawn in and raised to tank pressure is moved through duct 18 and into the tank. At the same time, the valve 19 is again opened so that the pressure on the rear of the moving piston is also at tank pressure. On the return stroke the conditions are precisely the same as on the outward

stroke but reversed as to the two cylinders. When the primary piston has reached the limit of its inner stroke the parts are in the position illustrated in Figure 5. The cycle is then repeated.

It will be noted that during each single cycle of the compressor an amount of air equal to the volume drawn in through port 12 is added to the supply in the tank, and the pressure raised by an amount corresponding to this increment. The compression therefore takes place throughout the entire system and very little compression takes place in the cylinders. This means that the load is substantially uniform throughout the compression stroke and that comparatively little heat is generated within the cylinder, the attendant advantages of this being well understood by those skilled in the art. The outward movement of the secondary piston does not compress any air above tank pressure, but does accelerate the movement of the air through the by-pass and assists in speedily bringing all of the air within the cylinder up to tank pressure. It has what may be described as a follow-up action.

I have refrained from describing the prime mover as it in itself forms no part of this invention. It is also to be understood that the operation of this prime mover is automatically controlled by the pressure in the tank so that when the pressure has been brought up to the required pressure, say one hundred pounds, the compressor stops and when this pressure falls the compressor is automatically started again.

I claim:

1. An air compressor comprising the combination of a tank, a compression cylinder, a piston in the cylinder, an intake valve, a discharge valve leading to the tank and means for introducing air at tank pressure into the cylinder at the termination of the intake stroke.

2. An air compressor comprising the combination of a tank, a compression cylinder, a piston in the cylinder, an intake valve and a discharge valve leading to the tank at one end of the cylinder, a duct leading to the tank communicating with the other end of the cylinder, and a by-pass at the end of the cylinder remote from the intake and discharge valves whereby air at tank pressure may pass around the piston at the end of the intake stroke and mingle with the intaken air.

3. An air compressor comprising the combination of a tank, a compression cylinder, a piston in the cylinder, an intake valve, a discharge valve leading to the tank, means for introducing air at tank pressure into the cylinder at the termination of the intake stroke and a duct connecting the cylinder behind the piston with the tank during the discharge stroke.

4. An air compressor comprising the com-

- 5 combination of a tank, a compression cylinder, a primary piston in the cylinder, a secondary piston carried by the primary piston, an intake valve and a discharge valve leading to the tank at one end of the cylinder, a duct leading to the tank communicating with the other end of the cylinder, a valve in the duct, means for moving the primary piston while the secondary piston remains relatively fixed, 6 a by-pass at the end of the cylinder remote from the intake and discharge valves whereby air at tank pressure may pass around the piston at the end of the intake stroke of the primary piston and mingle with the intaken air, 10 15 means for closing the valve in the duct at the end of the intake stroke of the primary piston, and means for moving the secondary piston to accelerate the movement of the air through the by-pass.
- 20 5. A double acting air compressor comprising the combination of a tank, a pair of cylinders, a piston in each cylinder, means connecting the two pistons so that they move in unison, intake and discharge valves near the 25 inner end of each cylinder, a duct leading from the discharge valves to the tank, a duct near the outer end of each cylinder leading to the tank, a control valve in each said duct, and means for reciprocating the pistons and 30 operating the valves whereby during each stroke atmospheric air is drawn into one cylinder and air at tank pressure moved from that cylinder into the tank while air at tank pressure is forced from the other cylinder into 35 the tank and air at tank pressure permitted to enter behind the moving piston in that cylinder. 40 6. A double acting air compressor comprising the combination of a tank, a pair of cylinders, a piston in each cylinder, means connecting the two pistons so that they move in unison, intake and discharge valves near the inner end of each cylinder, a duct leading from the discharge valves to the tank, a duct 45 near the outer end of each cylinder leading to the tank, a control valve in each said duct, a by-pass near the outer end of each cylinder, and means for reciprocating the pistons and operating the valves whereby during each 50 stroke atmospheric air is drawn into one cylinder and air at tank pressure moved from that cylinder into the tank while air at tank pressure is forced from the other cylinder into the tank and air at tank pressure permitted to enter behind the moving piston in that cylinder. 55 60 7. A double-acting air compressor comprising the combination of a tank, a pair of cylinders, a piston in each cylinder, means connecting the two pistons so that they move in unison, intake and discharge valves in each 55 60 65 70 75 80 85 90 95 100 105 110 115 120 125 130
- cylinder, the intake valves communicating with the atmosphere and the discharge valves communicating with the tank, means for reciprocating the pistons, means for opening the intake valve in one cylinder at the beginning of the intake stroke of the piston in that cylinder and means for opening the discharge valve in that cylinder at the end of the intake stroke whereby air at tank pressure is permitted to enter and mingle with the intaken air.
- In testimony whereof I affix my signature.
LAWRENCE H. HYATT.
